CLAIM

The ornamental design for a tubular member for a vehicle accessory, as shown and described.

DESCRIPTION

FIG. 1 is a perspective view taken from a bottom, front, left side of a portion of a tubular member according to an embodiment of our design;

FIG. 2 is a top plan view of the portion of the tubular member of FIG. 1, a bottom plan view being a mirror image thereof;

FIG. 3 is a cross-sectional view taken across the line 3-3 of FIG. 2;

FIG. 4 is a left side elevation view of the portion of the tubular member of FIG. 1; and,

FIG. 5 is a cross-sectional view taken across the line 5-5 of FIG. 4.

Throughout the Figures, where shown, the dashed lines are included for the purpose of illustrating portions of the article which form no part of the claimed design.

1 Claim, 3 Drawing Sheets
